EXTENDIBLE FOOTREST FOR EASY CHAIRS

Linus Johnson, New York, N. Y.

Application October 31, 1938, Serial No. 237,946

6 Claims. (Cl. 155—170)

This invention relates to new and useful improvements in an extendible footrest for easy chairs.

The invention has for an object the construction of a footrest which is characterized by a footrest board supported in a particular manner so as to normally be disposed beneath the seat of the easy chair and to be extendible to a raised position to the front of the chair.

More specifically, the invention proposes a novel construction for supporting the footrest in its retracted, and in its extended position.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an easy chair constructed according to this invention and shown with the footrest in its retracted position.

Fig. 2 is a perspective view of the easy chair showing the footrest partially extended.

Fig. 3 is a perspective view of the chair showing the footrest fully extended.

Fig. 4 is a plan view of the extendible footrest per se illustrated in the fully retracted position.

Fig. 5 is an elevational view looking in the direction of the line 5—5 of Fig. 4 but illustrating the footrest attached to the back portion of the easy chair.

Fig. 6 is a longitudinal sectional view taken on the line 6—6 of Fig. 4 but illustrating the footrest attached to the bottom of the easy chair.

Fig. 7 is a transverse sectional view taken on the line 7—7 of Fig. 4 but illustrating the footrest attached to the bottom of the chair.

Fig. 8 is a perspective view of the lower right hand corner of Fig. 4.

Fig. 9 is a view similar to the view shown in Fig. 8 but illustrating the footrest in a partially extended position.

Fig. 10 is a view similar to Fig. 6 but illustrating the footrest in its fully extended position.

Fig. 11 is an elevational view looking in the direction of the line 11—11 of Fig. 10.

Fig. 12 is a fragmentary enlarged detailed view of a portion of Fig. 3.

Fig. 13 is a plan view of a modified form of the invention.

Fig. 14 is a vertical sectional view taken on the line 14—14 of Fig. 13.

Fig. 15 is a fragmentary vertical sectional view taken on the line 15—15 of Fig. 14.

Fig. 16 is a horizontal sectional view taken on the line 16—16 of Fig. 15.

Fig. 17 is a view taken on the line 17—17 of Fig. 16.

The extendible footrest for easy chairs, according to this invention, includes a pair of spaced parallel tracks 10 suspended at their ends to the underside of an easy chair 11. At the rear ends of the tracks 10 are formed with upwardly bent portions 10^a which are secured by fastening elements 12 to a portion of the easy chair 11 located beneath the seat of the easy chair and above the legs thereof. At the front ends 10^b the tracks 10 are supported by hangers 13. Each hanger 13 has top portions 13^a and 13^b by which it is attached to the underside of the chair 11. There is a depending portion 13^c on each of the hangers which supports the front end of the track 10.

A U-shaped member 15 is provided for each of the tracks 10 and has its arms 15^a and 15^b, respectively, extended along the sides of and parallel to the tracks 10. These members 15 have their centers 15^c slidably supported on the tracks 10. The U-shaped members are each formed from two strips of material forming the side arms thereof and these strips have their inner ends bent towards each other and overlapping and welded or in any other manner secured together to form the centers 15^c. Each of the centers 15^c is formed with an opening through which the track 10 passes. The hangers 13 are also formed with downward extending U-shaped portions 13^d which serve to slidably support one of the arms of the U-shaped members. Particularly, it is the outer arms 15^b which are supported by the hangers 13. The arrangement is such that the U-shaped members may be moved from their inward position, illustrated in Figs. 1, 4, 5 and 6, to extended positions illustrated in Figs. 9 and 10.

A rod 17 is mounted between the front ends of the arms of the U-shaped members 15. Spacer elements 18 are mounted upon the rod 17 between the ends of the arms of each pair of members 15 to assist in rigidly holding the arms in parallel relationship with each other. Other tubular spacer members 19 are also mounted on the rod 17 inside of the arms 15^a of the U-shaped members and assist in properly holding a pair of legs 20 as hereinafter more fully explained.

The legs 20 are pivotally mounted at their upper ends on the rod 17 at positions immediately to one side of the bushings 19. These legs 20 are

20

25

30

35

40

45

50

55

adapted to extend vertically downwards to rest on the ground, or floor, as illustrated in Figs. 3, 9, 10 and 11. Or these legs may be pivoted to horizontal positions to extend within the plane 5 of the members 15 as illustrated in Figs. 2, 5, 6, 7 and 9.

A footrest board 21 is of a width so as to extend across the inner arms 15^a of the members 15. Bars 22 are pivotally connected with the footrest 10 21 and with the inner arms 15^a of the U-shaped members for supporting the footrest in its raised position. More specifically, there are four 15 of these bars 22. They are arranged at the four corners of the footrest. Each of these bars is pivotally connected by pintles 23 with brackets 24 attached upon the bottom face of the footrest. At their lower ends the bars 22 are pivotally mounted by pintles 25 on the side arms 15^a. The bars 22 are of identical length and they are arranged parallel to each other so as to produce a parallelogram in conjunction with the footrest 21 and the side arms 15^a. Therefore the footrest 21 may move from the full line position shown in Fig. 9, for example, to the dot and dash line position shown in this figure.

Links 27 are connected between the legs 20 and the footrest 21 for raising the footrest when the legs are moved to their vertical positions. More particularly, the links 27 are supported at their lower ends by pintles 28 mounted upon the legs 29. At their upper ends the links 27 are pivotally supported by certain of the pintles 23 and certain of the brackets 24. There is a particular relationship between the links 27 and the bars 22. This relationship is such that when the legs 29 are in their vertical positions, as shown in Fig. 10, the footrest will be in a raised position.

When the legs 20 are pivoted to the horizontal positions the pins 23 will move along the arcuate line A in Fig. 10, and simultaneously the pins 23 at the upper ends of the links 27 will move along the arcuate line B. The parts are so proportioned that when the legs 20 are disposed in the same plane as the U-shaped members 15, the bars 22 will also be disposed within this plane and the foot rest 21 will be rested across the arms 15^a of the U-shaped members.

A means is also provided for extending and retracting the members 15. This means includes a lever 30 which is pivotally mounted intermediate of its ends by a pintle 31 mounted upon the bottom portion of the easy chair 11. One end 30^a of the lever 30 projects and is bent upwards to form a handle which may be manually gripped to move the lever. The inner end of the lever 30 is pivotally connected with a bushing 32 which is slidably supported on a rod 33 mounted between the inner ends of the U-shaped members.

A bar 29^a is rigidly connected between the legs 28 and holds the legs together as a unit.

The operation of the device is as follows:

A person may sit in the easy chair while it is in the condition illustrated in Fig. 1. The footrest may be extended by first gripping the end 30^a of the lever 30 and moving this end rearwards. As the end of the lever is moved rearwards its inner end will move forwards (see Fig. 4), and the bushing 32 will be correspondingly moved and slide along the rod 33 and correspondingly move the rod 33. This will cause the U-shaped members 15 to be moved to extended positions as illustrated in Fig. 2. Then the foot rest board 21 may be manually gripped and pulled upwards to the position illustrated in Fig. 3 and this automatically pivots the legs 20 downwards

to their vertical positions as shown in Figs. 3 and 10. The footrest 21 is now fully opened and ready for use.

The footrest board 21 illustrated in Figs. 13 and 14, is provided with a folded flap 21' hinged at 21^a. A projecting loop 35 is mounted on the bottom face of the flap 21'. A latch arm 37 has a hook 36 formed on its free extremity and in the open position of the flap 21' the hook 36 is adapted to be engaged upon the loop 35 for rigidly supporting the flap. The other end of this arm is slidably connected in channel 38 secured to one of the legs 20. The latch arm 37 may be raised or lowered and held in each position by a suitable wing nut 39 which engages a threaded portion 40 projecting from slide block 41 which is hinged to the lower extremity of the latch arm 37, at 42. This arrangement permits the flap to be extended and held firmly in position so that books, or other objects may be placed thereon.

In place of the above sliding arm arrangement, the hinged latch arm 37 may be foldingly arranged to hold the flap 21' in open position, and when the hinged flap 21' is not used, the folding latch arm may be closed.

While I have illustrated and described the preferred embodiments of my invention, it is to be understood that I do not limit myself to the precise constructions herein disclosed and the right is reserved to all changes and modifications 30 coming within the scope of the invention as defined in the appended claims.

Having thus described my invention, what I claim as new, and desire to secure by United States Letters Patent is:

1. An extendible footrest for easy chairs, comprising a pair of spaced parallel tracks suspended at their ends beneath the seat of an easy chair, a U-shaped member for each of said tracks having its arms extended along the sides of and parallel to said track and having its center slidably supported on the track, hangers suspended beneath the seat of said chair and slidably supporting one of the arms of each of said members, a rod between the front ends of said arms, a pair of legs pivotally mounted on said rod and adapted to extend vertically downwards to rest on the floor or horizontally within the plane of said members, a footrest board rested across the inner arms of said members, bars pivotally connected with said footrest and said inner arms for supporting the footrest in its raised position, links between said legs and footrest for raising the footrest when the legs are moved to their vertical position and means for extending and retracting said members.

2. An extendible footrest for easy chairs, comprising a pair of spaced parallel tracks suspended at their ends beneath the seat of an easy chair, a U-shaped member for each of said tracks having its arms extended along the sides of and parallel to said track and having its center slidably supported on the track, hangers suspended beneath the seat of said chair and slidably supporting one of the arms of each of said members, a rod between the front ends of said arms, a pair of legs pivotally mounted on said rod and adapted to extend vertically downwards to rest on the floor or horizontally within the plane of said members, a foot-rest board rested across the inner arms of said members, bars pivotally connected with said footrest and said inner arms for supporting the footrest in its raised position, links between said legs and footrest for raising the footrest when the legs are moved to their 75

vertical position, and means for extending and retracting said members, each of said U-shaped members comprising a pair of strips forming the arms thereof and having their rear ends bent towards each other and overlapping and forming the centers thereof.

3. An extendible footrest for easy chairs, comprising a pair of spaced parallel tracks suspended at their ends beneath the seat of an easy chair, a U-shaped member for each of said tracks having its arms extended along the sides of and parallel to said track and having its center slidably supported on the track, hangers suspended beneath the seat of said chair and slidably supporting one of the arms of each of said members, a rod between the front ends of said arms, a pair of legs pivotally mounted on said rod and adapted to extend vertically downwards to rest on the floor or horizontally within the plane of said members, a footrest board rested across the inner arms of said members, bars pivotally connected with said footrest and said inner arms for supporting the footrest in its raised position, links between said legs and footrest for raising the footrest when the legs are moved to their vertical position, and means for extending and retracting said members, said hangers being provided with downwardly projecting portions supporting the front ends of said tracks.

30 4. An extendible footrest for easy chairs, comprising a pair of spaced parallel tracks suspended at their ends beneath the seat of an easy chair, a U-shaped member for each of said tracks having its arms extended along the sides of and parallel to said track and having its center slidably supported on the track, hangers suspended beneath the seat of said chair and slidably supporting one of the arms of each of said members, a rod between the front ends of said arms, a pair of legs pivotally mounted on said rod and adapted to extend vertically downwards to rest on the floor or horizontally within the plane of said members, a footrest board rested across the inner arms of said members, bars pivotally connected with said footrest and said inner arms for supporting the footrest in its raised position, links between said legs and footrest for raising the footrest when the legs are moved to their vertical position, means for extending and retracting said members, said bars being arranged parallel to each other and forming a parallelogram in conjunction with said footrest and the associated arm portion of the U-shaped member.

50 5. An extendible footrest for easy chairs, comprising a pair of spaced parallel tracks suspended

at their ends beneath the seat of an easy chair, a U-shaped member for each of said tracks and having its arms extended along the sides of and parallel to said track and having its center slidably supported on the track, hangers suspended beneath the seat of said chair and slidably supporting one of the arms of each of said members, a rod between the front ends of said arms, a pair of legs pivotally mounted on said rod and adapted to extend vertically downwards to rest on the floor or horizontally within the plane of said members, a footrest board rested across the inner arms of said members, bars pivotally connected with said footrest and said inner arms for supporting the footrest in its raised position, links between said legs and footrest for raising the footrest when the legs are moved to their vertical position, and means for extending and retracting said members, comprising a lever pivotally mounted beneath the seat of said easy chair and having an extended end which may be moved, a bar between said U-shaped members, a bushing slidably mounted on said bar, and the inner end of said lever being pivotally connected with said bushing.

6. An extendible footrest for easy chairs, comprising a pair of spaced parallel tracks suspended at their ends beneath the seat of an easy chair, a U-shaped member for each of said tracks having its arms extended along the sides of and parallel to said track and having its center slidably supported on the track, hangers suspended beneath the seat of said chair and slidably supporting one of the arms of each of said members, a rod between the front ends of said arms, a pair of legs pivotally mounted on said rod and adapted to extend vertically downwards to rest on the floor or horizontally within the plane of said members, a footrest board rested across the inner arms of said members, bars pivotally connected with said footrest and said inner arms for supporting the footrest in its raised position, links between said legs and footrest for raising the footrest when the legs are moved to their vertical position, means for extending and retracting said members, comprising a lever pivotally mounted beneath the seat of said easy chair and having an extended end which may be moved, a bar between said U-shaped members, a bushing slidably mounted on said bar, and the inner end of said lever being pivotally connected with said bushing the outer end of said lever having a bent up portion forming a handle.

LINUS JOHNSON.
